UNITED STATES PATENT OFFICE.

WALTER J. WHITEHEAD, OF HACKENSACK, NEW JERSEY.

FLUSH-TANK.

1,192,588.

Specification of Letters Patent. Patented July 25, 1916.

Application filed May 22, 1914. Serial No. 840,164.

To all whom it may concern:

Be it known that I, WALTER J. WHITEHEAD, a citizen of the United States, and residing at Hackensack, in the county of Bergen and State of New Jersey, have invented certain new and useful Improvements in Flush-Tanks, of which the following is a specification, such as will enable those skilled in the art to which it appertains to make and use the same.

This invention relates to flush tanks for use in connection with watercloset basins, and the object thereof is to provide an improved device or apparatus of this class, particularly designed for use in connection with what are known as low-down tanks or tanks which are supported at a short distance above the closet basin; a further object being to provide a flush tank mechanism which operates on the principle of a siphon and with which the flow or discharge of the water can be quickly and easily effected by means of a crank shaft, push-button or any other suitable construction, and which will be both positive and effective in operation; and with these and other objects in view the invention consists in a flush tank apparatus constructed and operating as hereinafter described and claimed.

The invention is fully disclosed in the following specification, of which the accompanying drawing forms a part, in which the separate parts of my improvement are designated by suitable reference characters in each of the views, and in which:

Figure 1 is a longitudinal vertical section of a flush tank involving my invention and looking forward; Fig. 2 a partial section on the line 2-2 of Fig. 1; and, Fig. 3 a section on the line 3-3 of Fig. 1.

In the practice of my invention, I provide a main flush tank *a* of the usual or any preferred construction, and the bottom of which is provided with a discharge pipe *b*. The pipe *b* is provided above the bottom of the main tank with a flange *b*² between which and the bottom of said tank is placed a packing gasket *b*³ and, in practice, the pipe *b* is passed downwardly through the bottom of said tank and is threaded and provided below said bottom with a nut *b*⁴, and by means of this construction the pipe *b* may be secured in the bottom of the main tank in such manner as to prevent any leakage of water therefrom.

Placed in or supported in the main tank

a is a supplemental tank *c*, the bottom of which is at a predetermined distance from the bottom of the main tank as shown at *c*², this distance being approximately the same as the height of the head *b*⁵ of the pipe *b* within said main tank. The supplemental tank *c* is provided at the bottom thereof with a lateral extension *c*³ in the bottom of which is a large valve aperture *c*⁴ closed by a heavy plate valve *c*⁵ pivoted at one side edge as shown at *c*⁶. The aperture *c*⁴ ranges transversely of the lateral extension *c*³ of the tank *c*, in the construction shown, and the valve *c*⁵ is similarly arranged.

Connected with the top of the lateral extension *c*³ of the tank *c* are a plurality of siphon tubes *d* which are preferably five in number. The pipe *b* is preferably a two-inch pipe and the siphon tubes *d* would, in this event, be three-quarter inch tubes, and the longer legs *d*² of the siphon tubes *d* are connected with or secured in the closure head *b*⁶ of the discharge pipe *b*. The closure head *b*⁶ of the discharge pipe *b* may be secured to said pipe in any desired manner, or may be formed integrally therewith, and in order that five siphon tubes may be secured in the head *b*⁶ of said pipe *b*, the said head *b*⁶ must be enlarged as shown in Fig. 1, and this enlargement is so effected, in practice, as to maintain the circular form thereof.

Within the supplemental tank *c* is placed a vertically movable float plunger *e* with the top of which is loosely connected a link *e*² and passing transversely through the top portion of the tank *a* is a shaft *f* having an arm *f*² which is connected with the link *e*², and the shaft *f* is provided at its free end with a crank handle *f*³, and by moving said crank handle in the direction of the arrow *x* the plunger *e* will be forced downwardly as will be readily understood.

In practice, the main tank *a* is supplied with water in the usual manner, the means for accomplishing this being not shown, and this supply of water to said tank *a* is automatic and is automatically cut off in the usual manner by the rising of the water in said tank, and with the construction shown the water never rises above the point shown at *g*. As the water enters the tank *a* and rises therein the valve *c*⁵ is lifted or raised, and the water flows into the supplemental tank *c* and rises therein, and raises the float plunger *e*, and in this operation,

or at the end thereof, the bends or loops d^3 of the siphon tubes are from one and one-half to two inches above the level of the water. If now, the operation of flushing is desired, the crank handle f^3 of the shaft f is moved in the direction of the arrow x , but only to a slight extent, and this operation forces the float plunger e downwardly and closes the valve c^5 and the water rises 10 in the shorter legs of the siphon tubes d to and above the point d^3 and a flow of water through the longer legs d^2 of the siphon tubes d is established and, in this operation, the valve c^5 is opened, and remains 15 open after the flow of water through the siphon tubes d ceases, or the pressure of the water in the tank a on the bottom of the valve c^5 is sufficient to open said valve, at which time the flow of water through the siphon tubes d will cease and the water will 20 again rise in the tank c and will flow into the tank a , as hereinbefore described and in the usual manner.

One of the chief features of this invention 25 is in the use of a number of small siphon tubes d instead of using one or more large tubes for the reason that the siphon flow of water, or the flow of water through the siphon construction may be much more 30 quickly and easily started, when a number of small tubes are used than when a large tube or tubes is used.

My invention, however, is not limited to 35 the number of siphon tubes d nor to the size thereof, nor to the size of the pipe b , but as a general proposition the capacity of the siphon tubes d should be equal to, or greater than the capacity of the discharge pipe b , and changes in and modifications of the 40 various parts of my improved flush tank apparatus, as herein shown and described may be made, within the scope of the appended claims, without departing from the spirit of my invention or sacrificing its 45 advantages.

Having fully described my invention, what I claim as new and desire to secure by Letters Patent, is:—

1. In an apparatus of the class described, 50 a main flush tank, a main discharge pipe secured in the bottom thereof and which extends upwardly thereinto, and the end of which within said tank is closed, a supplemental tank placed in the main tank and the bottom of which is above the bottom of the main tank and provided with a valve which opens upwardly, a plunger float placed in the supplemental tank, and a plurality of siphon tubes, the shorter legs 55 of which are connected with the bottom portion of the supplemental tank and the longer legs of which are connected with the discharge pipe, 60

longer legs of which are connected with the discharge pipe.

2. In an apparatus of the class described, a main flush tank, a main discharge pipe 65 secured in the bottom thereof and which extends upwardly thereinto, and the end of which within said tank is closed, a supplemental tank placed in the main tank and the bottom of which is above the bottom of the main tank and provided with a valve which opens upwardly, a plunger float placed in the supplemental tank, and a plurality of siphon tubes, the shorter legs of which are connected with the bottom portion of the supplemental tank and the longer legs of which are connected with the discharge pipe, the combined capacity of said siphon tubes being the same or greater than the capacity of the discharge pipe. 70

3. In an apparatus of the class described, a main flush tank, a supplemental tank placed therein, the bottom of which is above the bottom of the main tank and is provided with a valve which opens upwardly, said bottom of the supplemental tank being also provided with a lateral extension, a float plunger placed in the supplemental tank, a discharge pipe secured in the bottom of the main tank and the end of which within said tank is closed, and a plurality of siphon tubes the shorter legs of which are connected with the extension of the supplemental tank and the longer legs with the closed end of the discharge pipe. 80

4. In an apparatus of the class described, the combination of a flush tank, a main discharge pipe associated therewith, a plurality of siphon tubes each of relatively small cross sectional area as compared with the main discharge pipe, the longer legs of the tubes being connected with said main discharge pipe and means for starting a flow through said tubes. 90

5. In an apparatus of the class described, the combination of a flush tank, a main discharge pipe associated therewith, a plurality of siphon tubes, each of relatively small cross sectional area as compared with the main discharge pipe, the longer legs of the tubes being connected with said main discharge pipe, whose entrance is otherwise closed, and means for starting a flow through said tubes. 100

In testimony that I claim the foregoing 105 as my invention I have signed my name in presence of the subscribing witnesses this 20th day of May 1914.

WALTER J. WHITEHEAD.
